CONTROL MEANS FOR BUTTONHOLING APPARATUS

William T. Leonard, Reading, Pa., assignor to Textile Trimming & Boarding Machine Co., Inc., Reading, Pa., a corporation of Pennsylvania

Application November 3, 1951, Serial No. 254,745

6 Claims. (Cl. 112—68)

1

The present invention relates to control means for buttonholing apparatus, such, for example, as a buttonhole stitching and cutting machine, and, more particularly, to a strand or thread continuity operated arrangement for controlling the cutting instrumentality of buttonholing apparatus.

Machines for automatically stitching buttonholes are available which perform a complete stitching operation following which the buttonhole is cut. When the thread in the machine breaks, a special repair job on the workpiece is necessary due to the fact that the buttonhole is cut before it is fully or properly stitched. The present invention provides a strand or thread continuity operated device which prevents the buttonhole cutting operation if the thread breaks or otherwise loses proper operating tension. Solely by way of example, the thread continuity operated arrangement of the present invention is shown in the setting of a buttonhole sewing machine of a well known type. The machine selected for illustrative purposes is the Singer sewing machine No. 71-101 manufactured by the Singer Manufacturing Company. A similar machine is the Singer sewing machine No. 71-107. Parts of these machines which are to be controlled in accordance with the present invention are described in a published booklet entitled "Instructions for Using and Adjusting Singer Sewing Machines 71-101 and 71-107." In the disclosure of the present invention given in conjunction with one illustrative embodiment, the machine selected as a setting will be described in detail only insofar as is necessary to an understanding of the invention and its functioning. Also, for purposes of illustration, certain of the parts of the machine are shown in slightly altered form.

The invention disclosed herein resides in the provision of a unitary control device of novel form which can be installed in an existing machine without, or substantially without, modification thereof. The invention also resides in the novel cooperation of the device provided by this invention with the mechanism with which it is associated.

The primary object of the present invention is to provide a novel strand or thread continuity operated arrangement for controlling operation of a sewing machine.

Another and related object of the invention is to provide novel means for preventing the cutting of a buttonhole in the process of being finished upon breakage of the buttonhole stitching thread.

2

A further object of the invention is to provide a unitary device which can be readily installed in an existing buttonhole machine whereby to prevent operation of a part or parts of the existing machine in the event of thread breakage.

Other objects and advantages of the invention will, of course, become apparent and immediately suggest themselves to those skilled in the art to which the invention is directed from a reading of the following specification in connection with the accompanying drawing in which:

Fig. 1 is a fragmentary perspective view of a buttonhole stitching and cutting machine including a device constructed in accordance with the present invention;

Fig. 2 is a fragmentary view in plan of the machine of Fig. 1 including only parts thereof which are referred to in describing the functioning of the present invention;

Fig. 3 is a fragmentary view in side elevation of the parts of Fig. 2 and;

Fig. 4 is a view in perspective of the device of this invention which is to be installed in an existing machine.

Referring to the drawing, and for the present to Fig. 1 thereof, there is shown a portion of a machine 10 for making buttonholes in a work piece such as a shirt. The machine 10 is of standard make, as stated above, and therefore only the parts of the machine actuated or controlled in accordance with the present invention will be described in detail. The forwardly extending arm 12 of the machine is provided with a head 14 which houses the needle bar 16 and its driving mechanism (not shown). The top rear portion 18 of the arm 12 houses the needle vibrating mechanism and part of a stitch control mechanism not essential to an understanding of the present invention for controlling certain steps in the stitching process known as "barring" whereby the ends of the buttonhole are finished with a bar stitch.

The course of the stitching thread 19 is shown in Fig. 1 of the drawing. The thread is stored in an unwinder rack (not shown) or any convenient reel and it passes downwardly through a hole 21 in the top of a thread leader post 22. The thread emerges through a hole 24 and passes to a tension device 26 provided with the usual discs. The tension device 26 is controlled by a rod 28, the purpose of which is not directly concerned with the present invention. From the tension device, the thread goes to a thread guide 31 and from there to a tensioning device 33. From the tensioning device 33, the thread

19 goes to a spring takeup 34. A tension thread guide 36 guides the thread (in the absence of the device 38 of the present invention) through a hole in the end of a thread take-up lever 41 and from there into a slot 43 in the face plate of the head 14. From the slot, the thread goes into the eye of the needle 46.

With the device 38 of this invention installed in the machine 10, the thread 19 is led from the thread guide 36 under a hook 51 at the end of the downwardly extending rod 53 of the device 38. The functioning of the device 38 will be described more in detail hereinafter. From the preceding description it will be seen that when the tension of the thread is maintained, the rod 53 will be biased upwardly as viewed on Fig. 1 of the drawing.

The needle 46 cooperates with a work piece which is moved by a work piece clamping device 56. The latter executes a path which is suitable for stitching the sides and ends of a button-hole. Since the specific form of work piece clamping device and its function is not directly a part of the present invention, its functioning and control will not be further described.

Cutting of the buttonhole is accomplished by a knife 58 clamped in a knife holder 59. The latter is mounted at the end of a knife bar 63. A downward thrust, for cutting purposes, is imparted to the bar 63 by a knife bar driving lever 66 which is pivoted on a knife bar driving lever hinge screw 68 which is received in a tapped hole in the arm 12. A knife bar connecting link (not shown) couples the lever 66 to the bar 63. A knife bar driving lever spring 71 anchored by a knife bar driving spring screw 73, biases the lever 66 and the bar 63 upwardly.

A driving stroke for the knife bar driving lever is imparted by an intermediate knife bar driving lever 76 through an intermediate knife bar driving lever connecting link 78. The latter is provided with a slot 81 which receives a screw stud 83 secured to the lever 66. Pivotal connection for the link 78 is provided by a hinge screw 84. The slot 81 and the screw 83 in conjunction with a knife bar disengaging lever 86 provides a controlled lost motion connection. The lever 86 is pivoted to the link 78 by means of a hinge screw 88. The lever 76 is pivoted to the machine body (fragmentarily shown) by means of a cap screw 89. An intermediate knife bar driving lever roller 92, secured to a part of the stop mechanism (not shown), operates the knife driving lever system described above.

The knife bar disengaging lever 86 is provided with a shoulder 94 which can engage the screw stud 83 to cause the lever 66 to be rocked when the right hand end of the lever 76 rises. This drives the knife 58 downwardly to cut the buttonhole. An arm 96 extending from the knife bar disengaging lever 86 rests on a tongue 99 which extends upwardly from a knife bar disengaging lever catch 101. The catch 101 is pivotally mounted at the end of a fixed bracket 103 by means of a hinge screw 106 and a nut 108. The catch 101, as shown in Fig. 2, is angularly shaped, being composed of two arms 111 and 112. The arm 111, as described above, is pivoted on the bracket 103 by means of the hinge screw 106.

The arm 112 is provided with a roller 114 which is periodically engaged by a disengaging lever catch tripping point 116. The latter is carried by a collar 118 mounted on a shaft 121 which is driven by a feed driving gear 124. The gear 124 meshes with a gear 125 connected to the cycling

mechanism of the machine 10. A spring 126 anchored to the bracket 103 serves to bias the knife bar disengaging lever to the left as viewed in Fig. 1. A spring 128 biases the knife bar disengaging lever catch in a clockwise direction as viewed in Fig. 2. A stop 129 for the catch 101 is schematically shown.

The parts thus far described are part of the sewing machine for sewing and cutting button-holes. As pointed out above, the showing of these parts is modified for the sake of convenience of illustration. The unitary control device 38 of novel form, which can be installed in the machine so far described by way of a setting for the present invention, will now be described together with the manner of its functioning in cooperation with the sewing machine parts. Fig. 4 of the drawing will be referred to for the present in describing the device 38. A plate member 141 is notched as indicated at 143 so that it will fit around the supporting pin for the tension device 26 previously described or any other convenient part of a sewing machine. A hole 146 receives a screw 147 of the machine 10 which supports a thread guide. A downwardly extending bracket 149 provides pivotal support for a pair of arms 151 and 152. These arms are rigidly connected and are pivoted to the bracket 149 by means of a pintle or hinge screw 154. The arm 151 carries the previously described rod 53 which is provided with the hook 51.

The arm 152 has an arm 156 pivoted thereon by means of a hinge screw 158. The arm 156 has laterally extending tongue 159 and a tongue 161. The unitarily joined arms 151 and 152 have a rod 164 connected thereto upon which a counter-weight 166 is adjustably slidable. A set screw 163 can be used to fix the position of the counter-weight 166.

In operation of the machine 10 with the device 38 installed therein, so long as the thread 19 is intact, the arm 151 is raised and the tongue 159 does not interfere with operation of the knife bar disengaging lever 86. With the thread unbroken, when the point 116 trips the knife bar disengaging lever catch 101, the tongue 99 is withdrawn which permits the shoulder 94 on the lever 86 to engage the screw stud 83 and effect a button-hole cutting operation.

When the thread 19 breaks, the arm 151 drops by gravity and the laterally extending tongue 159 moves to the left as viewed in Fig. 1 to lie over the hinge screw 106. When the disengaging lever catch tripping point 116 moves the catch 101 to shift the tongue 99, the knife bar disengaging lever 86 is prevented from moving under the influence of the spring 126 by engagement of an inturned extension 171 with the laterally extending tongue 159 which rests on the hinge screw 106 at this time. The shoulder 94 cannot engage the screw stud 83 so that the lever 66 is not moved to drive the knife bar 63.

The invention claimed is:

1. A device for application to a buttonhole sewing machine having a workpiece cutter to prevent operation of the cutter in the event of sewing thread failure, said device comprising a bracket, means on said bracket to facilitate connection thereof to an existing stationary part of the sewing machine, a pair of rigidly joined arms pivoted to said bracket, said arms being angularly disposed with respect to each other, the first of said arms having a rod secured thereon to extend from said first arm substantially at a right angle, a hook at the end of said

rod for engagement with a tensioned sewing thread whereby to be supported by said thread, a member pivoted to the second of said arms adjacent its free end, said member having an extension substantially aligned with the body of said member, and a tongue extending laterally from said member.

2. A device for application to a buttonhole sewing machine having a workpiece cutter to prevent operation of the cutter in the event of 10 sewing thread failure, said device comprising a bracket, means on said bracket to facilitate connection thereof to an existing stationary part of the sewing machine, a pair of rigidly joined arms pivoted to said bracket, said arms being angularly disposed with respect to each other, adjustable biasing means associated with said arms, the first of said arms having a rod secured thereon to extend from said first arm substantially at a right angle, a hook at the end of said rod for engagement with a tensioned sewing thread whereby to be supported by said thread, a member pivoted to the second of said arms adjacent its free end, said member having an extension substantially aligned with the body of said member, and a tongue extending laterally from said member.

3. A device for application to a buttonhole sewing machine having a workpiece cutter to prevent operation of the cutter in the event of 30 sewing thread failure, said device comprising a bracket, means on said bracket to facilitate connection thereof to an existing stationary part of the sewing machine, a pair of rigidly joined arms pivoted to said bracket, said arms being angularly disposed with respect to each other, an adjustable counter weight secured to said arms, the first of said arms having a rod secured thereon to extend from said first arm substantially at a right angle, a hook at the end of said rod for engagement with a tensioned sewing thread whereby to be supported by said thread, a member pivoted to the second of said arms adjacent its free end, said member having an extension substantially aligned with the body of said member, and a tongue extending laterally from said member.

4. In a buttonhole sewing machine having means to perform a cutting operation on a workpiece, a knife, a first lever for driving said knife, a second lever, means to impart a driving stroke to said second lever, a link pivoted to said second lever, a lost motion connection between said link and said first lever, a member pivoted to said link for locking said lost motion connection, biasing means for said member, a trip for said mem-

ber, a pivotal support for said trip, a tongue on said member, and movable means controlled by thread tension for engagement between said tongue and said pivotal support, means whereby 5 said movable means is prevented from engaging said pivotal support by tension existing in a sewing thread, said movable means having means associated therewith to bias it for engagement with said pivotal support upon thread failure.

5. In a buttonhole sewing machine having means to perform a cutting operation on a workpiece, a knife, a first lever for driving said knife, a second lever, means to impart a driving stroke to said second lever, a link pivoted to said second lever, a slot in said link, a projection from said first lever movable in said slot to provide a lost motion connection between said link and said first lever, a member pivoted to said link for locking said lost motion connection, a trip for said member, a pivotal support for said trip, a tongue on said member, and movable means controlled by thread tension for engagement between said tongue and said pivotal support, means whereby 15 said movable means is prevented from engaging said pivotal support by tension existing in a sewing thread, said movable means having means associated therewith to bias it for engagement with said pivotal support upon thread failure.

20 6. In a buttonhole sewing machine having means to perform a cutting operation on a workpiece, a knife, a first lever for driving said knife, a second lever, means to impart a driving stroke to said second lever, a link pivoted to

25 said second lever, a lost motion connection between said link and said first lever, a member pivoted to said link for locking said lost motion connection, a trip for said member, a pivotal support for said trip, a tongue on said member, and movable means controlled by thread tension for engagement between said tongue and said pivotal support, means whereby 30 said movable means is prevented from engaging said pivotal support by tension existing in a sewing thread, said movable means having means associated therewith to bias it for engagement with said pivotal support upon thread failure.

35 7. In a buttonhole sewing machine having means to perform a cutting operation on a workpiece, a knife, a first lever for driving said knife, a second lever, means to impart a driving stroke to said second lever, a link pivoted to said second lever, a lost motion connection between said link and said first lever, a member pivoted to said link for locking said lost motion connection, a trip for said member, a pivotal support for said trip, a tongue on said member, and a second member controlled by thread tension 40 and being movable for engagement between said tongue and said pivotal support, means whereby said second member is prevented from engaging said pivotal support by tension existing in a sewing thread, said second member having means associated therewith to bias it for engagement with said pivotal support upon thread failure.

45 WILLIAM T. LEONARD.
